UNITED STATES PATENT OFFICE.

JOHN F. MARTIN, OF MARSHALL, MICHIGAN.

FENCE-POST.

SPECIFICATION forming part of Letters Patent No. 674,538, dated May 21, 1901.

Application filed October 19, 1900. Serial No. 33,573. (No model.)

To all whom it may concern:

Be it known that I, JOHN F. MARTIN, a citizen of the United States, residing at Marshall, in the county of Calhoun and State of Michigan, have invented a new and useful Fence-Post, of which the following is a specification.

The invention relates to improvements in fence-posts.

The object of the present invention is to improve the construction of fence-posts and to provide a simple and comparatively inexpensive post which will be practically indestructible and which will not be affected by the weather or the moisture of the ground.

The invention consists in the construction and novel combination and arrangement of parts hereinafter fully described, illustrated in the accompanying drawings, and pointed out in the claims hereto appended.

In the drawings, Figure 1 is an elevation of the wire column or framework of a post constructed in accordance with this invention, the cement being indicated in dotted lines. Fig. 2 is a horizontal sectional view of the

post. Fig. 3 is a perspective view of a wire column or framework, illustrating another form of the invention. Fig. 4 is a horizontal sectional view of the same. Fig. 5 is a perspective view illustrating another modification of the invention. Fig. 6 is a perspective view illustrating another form of the wire column or frame. Figs. 7 and 8 are perspective views showing columns or frames provided with angle-bars. Fig. 9 is a perspective view of a frame or column designed for a hitching-post. Fig. 10 is a horizontal sectional view of the frame or column illustrated in Fig. 8. Fig. 11 is an enlarged detail view of a portion of the wire column or framework shown in Fig. 1, illustrating the manner of connecting the wires.

Like numerals of reference designate corresponding parts in all the figures of the drawings.

1 designates a post consisting of a frame or column 2, embedded in a filling or body portion 3, consisting of cement or other plastic material, which is adapted to protect the column or frame from the weather and from the effects of the moisture in the ground, and the frame or column binds the plastic material and affords the necessary strength whereby a

fence-post is provided which will be practically indestructible. The fence-post tapers from the bottom to the top, and the column 55 or frame is also tapering to conform to the contour of the post, and it is approximately rectangular in cross-section, as illustrated in Fig. 2 of the accompanying drawings, each side of the frame or column consisting of longitudinal wires 4, disposed in zigzag form and forming a symmetrical design. The wires 4 are twisted together at the bottom of the frame or column at 5 and diverge therefrom toward the corners of the frame or column, 60 where they are twisted at 6 around the wires of the adjacent sides. From these points the wires 4 converge and are twisted together directly above the twisted portion 5. The wires are laced back and forth in this manner, forming approximately diamond-shaped loops 65 which gradually decrease in size toward the top of the post, where all of the wires are united.

The post is provided at intervals at its upper portion with horizontal loops 7, projecting outward beyond the plastic body portion or filling and having alined openings which are adapted to receive a rod 8. The arms and the rod are designed for securing the fencing material to the post, and this fencing material may consist of boards, woven wire, horizontal wires or runners, or the like, and such fencing is readily applied to the post. The loops 7 are twisted to form solid shanks 8^a, 85 and they are preferably formed by a single continuous wire 9, laced back and forth within the frame or column and extended outward horizontally therefrom at intervals to provide the loops 7. After the wire column or frame is 90 formed the cement is applied by means of suitable molds and a solid fence-post is produced. The wires at the base of the wire frame or column are preferably formed into a horizontal rectangular base 10, having straight sides, 95 which may be either twisted or plain.

In Fig. 1 of the drawings conventional twists are shown for connecting the wires 4, which are laced back and forth, as before explained; but in Fig. 11 of the drawings the exact manner of twisting the wires together is illustrated.

In Fig. 3 of the accompanying drawings is illustrated another form of wire column or

frame, which consists of four approximately vertical wires 11, located at the centers of the sides of the frame or column and connected by four zigzagly-bent corner-wires 12. Each 5 of the corner-wires 12 is extended back and forth between the adjacent upright wires, and the connecting portions 13, which are inclined, are angularly bent to form a frame or column which is approximately rectangular 10 in horizontal section, as clearly shown in Fig. 4 of the accompanying drawings. The corner-wires, which are laced back and forth, are twisted together at their points of connection, and the upright wires are also twisted or 15 coiled around the corner-wires at the points where they are joined together. A rectangular base 14 is preferably formed at the bottom of the frame or column, which is also provided at intervals with horizontal loops 15, 20 arranged at the upper portion of the post and projecting beyond the body portion or filling to receive a vertical locking-rod 16. Each horizontal loop 15 is preferably constructed of a separate piece of wire twisted around 25 the wires of the frame or column and having one side extended to form a horizontal brace 17. The horizontal brace 17 extends across the wire frame or column and strengthens the same.

30 In Fig. 5 of the accompanying drawings the wire frame or column has a general circular or cylindrical form, and it is provided with a circular base 18, and it consists of four spirally-coiled wires 19, connected at their points 35 of intersection by separate wire ties 20, and each pair of spirally-coiled wires 19 forms a series of reversely-arranged approximately zigzagly-disposed inclined elliptical loops 21. The elliptical loops formed by one pair of 40 wires are connected at the centers of their sides by the elliptical loops formed by the opposite pair of wires. This form of frame or column is provided with twisted horizontal loops 22 for the reception of a locking-wire 23, 45 and each locking-wire is provided at its upper end with a hook for engaging the uppermost horizontal arm. The horizontal arms 22 are preferably formed by separate wires, each wire having an extension forming a horizontal brace 24, which extends across the elliptical loops and which is twisted around the same to dispense with the clips 20 at these points.

The column or frame shown in Fig. 7 of 55 the accompanying drawings is provided with two angle-bars 25 and 26, placed flat against each other and composed of sides or wings of unequal width and connected at intervals by rivets or other suitable fastening devices. 60 The ribs or flanges are provided at regular intervals with notches 27, and the frame or column is completed by a continuous wire coiled horizontally around the angle-bars in the notches. After each coil 28 is completed 65 the wire is extended diagonally to form an inclined connecting portion 29, which extends upward to the next set of notches, at which

point the wire is coiled horizontally to form another loop, and after the latter is completed it is extended upward to the next set of 70 notches or recesses. The inclined connecting portions 29 form a spiral brace extending from the bottom to the top of the post. Horizontal arms or loops 30 are formed at intervals by extending the wire which is twisted, as clearly 75 shown in Fig. 7. The twisted loops 30 are provided with eyes for the reception of a locking-rod 31.

The form of the column shown in Fig. 6 is substantially the same as that illustrated 80 in Fig. 3, with the exception that the column or frame is cylindrical. The column or frame is provided with the upright wires 11^a, arranged approximately vertical and located at opposite sides of the said frame or column. 85 Each of the wires 12^a is laced back and forth to provide curved connecting portions 13^a. The horizontal loops 15^a are secured to one of the vertical wires 11^a; but they may be extended across the frame or collar if desired. 90

Another form of the frame or column having angle-bars is illustrated in Fig. 8 of the accompanying drawings, and in this form of the invention the angle-bars 32 and 33 have their wings or flanges perforated for the reception of the coils 34, which are arranged on a slight slant and which are formed by a continuous wire. After each coil 34 is completed the wire is extended upward to the next set of perforations. The loops at one 95 side of the post are extended to form projecting eyes 35, which are located diametrically opposite the connecting portions 36.

The invention may be employed for other purposes than fence construction, and in Fig. 9 of the accompanying drawings is illustrated a frame which is adapted for hitching-posts. The frame is composed of upper and lower plates 37 and 38, connecting-wires 39, and a projecting loop 40. The connecting-wires 39 are preferably composed of twisted strands secured at their terminals to the plates, at the corners thereof, and the loop 40 is twisted to form an eye and extends centrally to form a top plate. The twisted loop 40 is designed 110 to project beyond the body portion or filling to afford means for connecting a hitching-strap to the post.

What I claim is—

1. A device of the class described comprising a body portion or filling of suitable material, and a skeleton frame or column embedded within the body portion or filling and provided at intervals throughout its length with loops located wholly within the said body portion or filling and extending entirely around the said frame or column, said loops being constructed of a continuous wire, substantially as and for the purpose described. 120

2. A device of the class described comprising a body portion or filling of suitable material, and a skeleton frame or column embedded in the said material and provided with a vertical series of loops located wholly within 130

the said body portion or filling, said frame or column being also provided with projecting wire loops extending outward from the frame or column beyond the body portion or filling 5 and forming a part of the said frame or column, said loops being disposed horizontally and arranged at intervals, substantially as described.

3. A device of the class described comprising a body portion or filling of suitable material, a skeleton frame or column embedded in the said material and provided at intervals with a vertical series of loops located wholly within the body portion or filling, said frame 10 or column being also provided at intervals with projecting horizontal loops forming a part of the column or frame and extending beyond the body portion or filling to form exterior eyes, and a locking-rod arranged in 15 the eyes, substantially as described.

4. A device of the class described comprising a body portion or filling of suitable material, and a frame or column embedded in the material and provided with a vertical series of wire loops extending from the top to 25 the bottom of the frame or column, and located wholly within the body portion or filling and consisting of continuous wires, said frame or column being also provided at intervals with projecting horizontal loops forming 30 exterior eyes, substantially as described.

In testimony that I claim the foregoing as my own I have hereto affixed my signature in the presence of witnesses.

JOHN F. MARTIN.
